DESIGN FOR A SERVICE PIN

John H. Williams, Zanesville, Ohio, assignor of
one-third to Patrick E. Flood and one-third to
Clarence J. Crossland, both of Zanesville, Ohio

Application October 8, 1942, Serial No. 108,464

Term of patent 7 years

To all whom it may concern:

Be it known that I, John H. Williams, a citizen of the United States, residing at Zanesville, and State of Ohio, have invented a new, original, and ornamental Design for a Service Pin, of which the following is a specification, reference being had to the accompanying drawing, forming a part thereof, where:

Fig. 1 is a front elevational view of the service pin showing my new design;

Fig. 2 is a top plan elevational view of the pin;
and

Fig. 3 is a side elevational view of the pin.

I claim:

The ornamental design for a service pin, substantially as shown.

JOHN H. WILLIAMS.
